INVENTOR

William Kent.

UNITED STATES PATENT OFFICE.

WILLIAM KENT, OF PASSAIC, NEW JERSEY.

STEAM-BOILER FURNACE.

SPECIFICATION forming part of Letters Patent No. 672,781, dated April 23, 1901.

Application filed October 17, 1900. Serial No. 33,355. (No model.)

To all whom it may concern:

Be it known that I, WILLIAM KENT, a citizen of the United States, residing at Passaic, in the county of Passaic and State of New Jersey, have invented certain new and useful Improvements in Furnaces for Steam-Boilers; and I do hereby declare the following to be a full, clear, and exact description of the invention, such as will enable others skilled in the art to which it appertains to make and use the same.

My invention relates to certain new and useful improvements in furnaces for steam-boilers, but especially for boilers of the water-tube type and to furnaces which use bituminous coal, lignite, peat, wood, tanbark, or other fuel which contains large quantities of tarry and gaseous matter and which in burning distils a large amount of combustible gases.

The object of this invention is to so construct and arrange the furnace that all of said gases will be consumed and the heat generated thereby utilized to the best advantage in the generation of steam; and with this end in view my invention consists in the details of construction and combination of elements hereinafter fully and in detail explained and then specifically designated by the claims.

In order that those skilled in the art to which my invention appertains may more fully understand its construction and adaptation, I will proceed to describe the same in detail, referring by letter to the accompanying drawings, forming part of this specification, in which—

Figure 1 is a vertical section of my furnace as applied to an ordinary horizontal return tubular boiler. Fig. 2 is a vertical cross-section through the boiler and the combustion-chamber in the rear of the bridge-wall. Fig. 3 is a horizontal cross-section of the furnace, taken over the bridge-wall at the line *a b* in Fig. 1.

C is the fire-chamber above the grate-bars.
D is the bridge-wall.

E is a combustion-chamber behind the bridge-wall.

F is a fire-brick arch or roof covering the greater portion of the combustion-chamber.

G G are two wing walls or baffle-walls

partly closing the passage through the combustion-chamber.

H H are several piers of fire-brick built in the rear of the bridge-wall.

I I represent a wall built above the arch *F* to prevent the passage of the gases above the arch.

In the operation of this furnace with ordinary grates and with bituminous coal or other gaseous fuel the alternate method of feeding coal is preferred—that is, the fresh coal is spread alternately on the right and left sides of the grate, an interval of some minutes of time elapsing between the feeding on the right and on the left sides. Immediately after fresh coal is put on one side of the furnace dense smoky gases arise from it, which in the ordinary boiler-setting would pass out of the chimney unburned, since in the ordinary setting there is no means provided for mixing with them an abundant supply of highly-heated air; but in this furnace such air is supplied through the bed of partially-burned and very hot coal and coke on the other side of the grate. The two currents, one of cool smoky gas arising from the fresh coal on one side of the grate and the other of clear and very hot gas containing a large excess of air, pass together over the bridge-wall *D*. Thence the two currents of gas pass under the fire-brick arch *F* and as they partly mingle greatly increase in temperature by reason of the combustion of a portion of the gases. When they reach the tall but narrow vertical opening between the wing walls *G G*, they are compelled to mix together thoroughly, and any smoky gas remaining in them being more highly heated is burned by the excess of hot air which is still present. The position of the wing walls is shown in the drawings to be near the rear end of the combustion-chamber; but it is evident that this position may be changed without materially altering their action; but I prefer to locate them at a considerable distance from the bridge-wall, as shown.

The wall *I I*, built above the arch, closes the passages through the two triangular-shaped spaces between the arch and the boiler, compelling the gases to pass beneath the arch. A small opening or openings may be left in

this wall to allow a portion of the gases to pass between the arch and the boiler. The piers H H behind the bridge-wall act as regenerators—that is, they absorb heat from the burned gasses at such times as they are most intensely heated and radiate or give up heat at such times as the gases are not so hot, as during the first minute after feeding fresh coal, when there is a great excess of freshly-distilled and rather cool gases.

By the means above described complete combustion of the smoky gases is secured when reasonable care is used by the fireman, and the resulting thoroughly-burned products of combustion are then in the right condition to be allowed to pass into the tubes and give up their heat to the water in the boiler.

Some advantages of the construction shown herein as compared with furnaces for horizontal tubular boilers having fire-chambers covered with fire-brick and wing walls in proximity to the bridge-wall, such as are shown in two former United States Letters Patent granted to me—viz., No. 320,563, dated June 23, 1885, and No. 604,158, dated May 17, 1898—are—

First. In new the construction in which there is no fire-brick roof over the fire-chamber the latter is kept comparatively cool, tending to prevent the fusing of the ash into clinker and the excessive radiation from the fire-doors, which are disadvantages common to brick-covered fire-chambers.

Second. The wing walls being placed at a considerable distance from the bridge-wall the currents of gas change their direction slowly, and therefore the draft is not checked, as it is with the sudden change of direction which takes place when the wing walls are near the bridge-wall, as in the earlier construction.

Third. The arch over the combustion-cham-

ber and the wing walls may be constructed within the ordinary setting of a horizontal tubular boiler without raising the boiler or occupying additional ground-space, which was necessary in the earlier construction.

Having thus described my invention, what I claim as new, and desire to secure by Letters Patent, is—

1. A furnace for a steam-boiler comprising the fire-chamber C and its bridge-wall D, located under the front portion of the boiler, the combustion-chamber E in the rear of the bridge-wall, the roof F over the combustion-chamber, a wall I I above the roof, obstructing the passage between the roof and the boiler, and the wing walls G G under the roof, substantially as shown and described.

2. A furnace for a steam-boiler comprising the fire-chamber C and its bridge-wall D, located under the front portion of the boiler, the combustion-chamber E in the rear of the bridge-wall, the roof F over the combustion-chamber, a wall I I above the roof, obstructing the passage between the roof and the boiler, the piers H H located in the rear of the bridge-wall, and the wing walls G G under the roof, substantially as shown and described.

3. In the setting of a horizontal steam-boiler in combination with a fire-chamber and bridge-wall, a combustion-chamber in the rear of the bridge-wall covered with a fire-brick arch, wing walls under the arch, and a wall above the arch obstructing the passage between the arch and the boiler, substantially as shown and described.

In testimony whereof I affix my signature in the presence of two witnesses.

WILLIAM KENT.
